Patented Feb. 13, 1917.

UNITED STATES PATENT OFFICE.

EDWIN A. GRUSHUS, OF MIDAS, NEVADA.

CINCH-GRIP.

1,216,228.

Specification of Letters Patent. Patented Feb. 13, 1917.

Application filed December 31, 1915. Serial No. 69,605.

To all whom it may concern:

Be it known that I, EDWIN A. GRUSHUS, a citizen of the United States, residing at Midas, in the county of Elko and State of Nevada, have invented certain new and useful Improvements in Cinch-Grips, of which the following is a specification.

This invention relates to cinch grips and is designed more particularly as an improvement upon the grip shown in my Patent No. 804,397, issued November 14, 1905, and the present invention aims to disclose several novel features of construction as distinguished from the patented grip, which features result in the attainment of certain advantages not present in the said patented structure.

It is one aim of the invention to so construct the grip that the tie strap of the saddle girth may be permanently connected at one end with the grip, thereby avoiding a bulge at the point of engagement of the said tie strap with the saddle ring and incidentally the invention aims to so construct the grip that the connection of the end of the tie strap therewith will not interfere with the closing together of the members comprising the grip and with the clamping action exerted by these members upon the said strap.

Another aim of the invention is to so construct the members comprising the grip that strain imposed upon the strap will result in the members being automatically brought together and held in such manner as to exert a maximum clamping force upon the strap.

The invention aims further to so construct the upper one of the clamping jaws of the grip that the strap may ride freely thereover when a pull is exerted upon the strap for the purpose of tightening the girth.

In the accompanying drawings:

Figure 1 is a vertical longitudinal sectional view through the grip applied.

Fig. 2 is a perspective view of the grip spread open.

Fig. 3 is a side elevation of the grip.

In the drawings the grip is illustrated as comprising hingedly connected members and one of these members includes side bars indicated by the numeral 1 connected at their lower ends by a cross piece 2 which is formed into a hook 3 designed for engagement with the girth strap ring indicated by the numeral 4. The side bars 1 at their upper ends are connected by a tubular cylindrical

cross bar 5 and below the said cross bar the said side bars are connected by a cross bar 6 upon which is rotatably fitted a roller 7. The other member of the grip comprises side bars 8 which are connected at their lower ends by a downwardly curved cross bar 9 and at their upper ends by a cross bar 10 which is circular in cross section and which rotatably fits within the tubular cross bar 5, the sections being thus hingedly connected to each other at their upper ends. The side bars 8 are further connected by a cross bar 11 which extends between the side bars below the cross bar 10 and upon which is rotatably fitted a roller 12. By reference to the drawings it will be observed that the upper ends of the side bars 8 or more specifically their portions which extend above the cross bar 11, are curved in the direction of the first described member of the grip and that the side bars 1 of the said first described member are straight from end to end. It will also be observed, and particularly by reference to Figs. 1 and 3 of the drawings, that the cross bar 11 is located in a plane above the cross bar 6 and the object in view in so relatively locating the cross bars 6 and 11 will be presently pointed out.

In order that the tie strap which is connected to the grip may be gripped by the grip in adjusted position, the first described member of the grip is provided with a gripping jaw indicated by the numeral 13. This jaw extends between the side bars 1 of the said member and is curved upwardly and laterally from the plane occupied by the said side bars and is provided with a smooth convex under surface indicated by the numeral 14. This jaw is located between the cross bar 6 and the connecting portion 2 and, as will be observed, extends in the direction of the second mentioned gripping member of the grip. The said second gripping member of the grip is provided with a similar jaw indicated at 15, which jaw extends between the side bars 8 and is curved upwardly and laterally in the direction of the first described member of the grip, it being noted, however, that it will be located below the jaw 13 when the members comprising the grip are closed. The upper surface of the jaw 15 is concave as will be observed by reference to Fig. 1 of the drawings, and is formed with transversely extending serrations indicated by the numeral 16. The ser-

rated concave face of the jaw 15, of course, opposes the smooth convex under surface of the jaw 13 and it is between these faces that the tie strap is to be gripped as will now be explained.

The tie strap is indicated in general by the reference numeral 17 and is permanently connected at one end as at 18 by being looped about the tubular cross bar 5. From 10 this cross bar the tie strap is led upwardly and through the saddle ring 19 and thence downwardly as shown in Fig. 1 and beneath the roller 7 and thence upwardly in front of the roller 12, after which it is 15 again passed through the saddle ring 19 and is led downwardly and finally passed between the jaws 13 and 15. When it is desired to tighten the strap a pull is exerted upon its end which extends beyond the 20 jaws 13 and 15. Upon the exertion of such strain the second described member of the buckle will be swung slightly away from the first described member as the strap runs over the serrated face of the jaw 15 and inasmuch as the convex under face of the jaw 13 is smooth, the strap will run freely there-over. The pull upon the strap will, of course, cause the same to be tightened, which will then bear heavily on the roller 12 which 25 in turn will bear on the bar 11, thus causing the second described member to be drawn in the direction of the first described member, and thus causing the jaw 15 to engage with the strap. It will be understood 30 that as the two members are drawn closer together, the space between the two jaws 13 and 15 becomes narrower, thus causing the strap to be gripped. In order to remove the saddle from the horse or to loosen the 35 girth, it is only necessary to place one finger under the bar 9 of the second described member, and by a light pull on the said bar 9 the said second described member may be drawn away from the first described member, thus releasing the grip on the strap. The strap may then be pulled in the opposite direction from that which it is pulled when tightening the girth, and after the 40 strap is made sufficiently loose the girth 45 ring 4 may be removed from the hook 3 allowing the saddle to be removed from the horse, the cinch grip being always left in position on the strap 17. Inasmuch as the 50 end of the strap is permanently connected 55 with the tubular cross bar 5 and this bar forms a part of that member of the grip including the side bars 1, the cross bar 10 will be permitted to have free pivotal movement within the tubular cross bar 5 and, 60 therefore, the drawing together of the two members of the grip will not be interfered with because of the connection of the strap end directly with the grip. By reason of the fact that the side bars 1 are straight 65 from end to end, the strain exerted upon

the grip will be in a direct line with the rings 4 and 19 and there will be no tendency for the grip to tilt or bulge at any point.

By reference to Figs. 2 and 3 of the drawings, it will be observed that the upper ends of the side bars 8 of the second described member of the grip are extended a short distance beyond the points of junction of the ends of the cross bar 10 with the said side bars, as indicated by the numeral 20, 75 and that these portions are designed to engage against shoulders 21 formed at the upper ends of the side bars 1 so as to limit the opening movement of the grip.

Having thus described the invention, what is claimed as new is:

1. In a grip of the class described, a member comprising spaced side bars, a tubular cross bar connecting the side bars at their upper ends, the said side bars being provided at their lower ends with attaching means, and a member including spaced side bars, a cross bar connecting the last mentioned side bars at their upper ends and rotatably fitting within the said tubular cross bar, the side bars of the second mentioned member having their upper end portions curved in the direction of the first mentioned member, the members being provided with co-operating gripping jaws, and a strap 85 permanently connected at one end about the tubular cross bar and arranged to be engaged between the said jaws.

2. In a grip of the class described, a member comprising spaced side bars, a tubular cross bar connecting the said bars at their upper ends, the said side bars being provided at their lower ends with attaching means, and a member including spaced side bars, a cross bar connecting the last mentioned side bars at their upper ends and rotatably fitting within the said tubular cross bar, the side bars of the second mentioned member having their upper end portions curved in the direction of the first mentioned member, the members being provided with co-operating gripping jaws, a cross bar connecting the side bars of the first mentioned member below the first mentioned cross bar, a cross bar connecting the 90 side bars of the second mentioned member below its first mentioned cross bar, the last mentioned cross bar being located above the third mentioned cross bar, and a strap 95 permanently connected with the said tubular cross bar and designed for engagement respectively beneath and against the third and last mentioned cross bars and to be gripped by the said jaws.

3. In a grip of the class described, 125 hingedly connected members, each including spaced side bars, a cross bar extending between the side bars of one member, a cross bar extending between the side bars of the other member, the last mentioned cross bar 130

being laterally offset with relation to the first mentioned cross bar and also with relation to the hinged connection between the said members, and the said last mentioned cross bar being located nearer the hinged connection than the first mentioned cross bar, a strap looped about the said cross bars and engaging the same and so arranged that when tensioned will exert lateral stress

in an inward direction against the last mentioned cross bar and thereby serve to swing said members together, and clamping jaws carried by the members and arranged to grip the said strap when the members are so swung.

15

In testimony whereof, I affix my signature.

EDWIN A. GRUSHUS. [L. S.]
